UNITED STATES PATENT OFFICE.

WILLIAM O. WADE AND RODERICK E. KERINS, OF NEW YORK, N. Y., ASSIGNEES TO
THOMAS & BETTS COMPANY, OF NEW YORK, N. Y., A CORPORATION OF NEW YORK.

DESIGN FOR AN ELECTRICAL RECEPTACLE.

41,218.

Specification for Design.

Patented Mar. 7, 1911.

Application filed June 1, 1908. Serial No. 436,166. Term of patent 14 years.

To all whom it may concern:

Be it known that we, WILLIAM O. WADE and RODERICK E. KERINS, both citizens of the United States, residing at New York, in the county and State of New York, have invented a new, original, and ornamental Design for Electrical Receptacles, of which the following is a specification, reference being had to the accompanying drawing, forming part thereof.

The figure is a view in side-elevation of

an electrical receptacle, showing our new design.

We claim—

The ornamental design for an electrical receptacle as shown.

WILLIAM O. WADE.
RODERICK E. KERINS.

Witnesses:

ALEXANDER C. PROUDFIT,
ADNAH McMURTRIE.
